W. GALANT

AQUARIUM

Filed Feb. 5, 1925

24 Inventor:
W. Galant.
By B. Pelechowicz
Attorney.

Attorney:

UNITED STATES PATENT OFFICE.

WLADYSLAW GALANT, OF CHICAGO, ILLINOIS.

AQUARIUM.

Application filed February 5, 1925. Serial No. 7,059.

To all whom it may concern:

Be it known that I, WLADYSLAW GALANT, a citizen of Poland, residing at Chicago, in the county of Cook and State of Illinois, **5** have invented certain new and useful Improvements in Aquariums, of which the following is a specification.

This invention relates to aquaria and its main object is the provision of a water-tight **10** aquarium.

A further object of the invention is the provision of an aquarium which can be easily assembled, which is durable in construction, and in which the minimum **15** amount of cement can be used, if any, in making the joints of the walls water-tight.

A still further object of the invention is the provision of an aquarium wherein the corner members supporting the side walls **20** are so firmly and efficiently anchored to the bottom of the aquarium that the necessity of any braces for further strengthening the structure of the aquarium is eliminated.

With the above general objects in view and **25** others that will appear as the nature of the invention is better understood, the same consists in the novel construction, combination and arrangement of parts hereinafter more fully described, illustrated in the accompanying drawing and pointed out in the appended claims.

In the drawing forming a part of this application, and in which like designating characters refer to corresponding parts **35** throughout the several views,

Figure 1 is a perspective view of the aquarium;

Figure 2 is an enlarged view partly in elevation and partly in section showing the **40** corner construction of the invention;

Figure 3 is a plane cross sectional view of the corner of the device taken on line 3—3 of Figure 1; and

Figure 4 is a vertical cross sectional view **45** taken on line 4—4 of Figure 2.

The invention consists of a wooden rectangular base 10 with side ledges 11 attached thereto by any suitable means such as nails **50** 12. The adjacent ends of the several ledges do not meet at the corners of said base, but are spaced permitting the insertion of vertically positioned corner members 13 which are likewise attached to said base. A metal tray 14 placed upon said base is held within **55** the ledges 11 and the corner members 13. If necessary to prevent any shifting of the tray

14 upon base 10 during the process of assembling the several parts of the aquarium, the tray may be affixed by its bottom to the base **60** 10 by means of nails 15. Preferably said nails are driven in the tray at points which subsequently will become covered by the glass walls later described so as to eliminate any possibility of leakage.

Each of said corner members 13 is substantially of L-shaped formation in horizontal cross section and has a molding or strip 16 longitudinally and angularly disposed therewithin. Said molding or strip has a wall or face 17 which is in oblique **70** relation in respect to the sides 19 of each corner member. The side walls 18 of said strip 16 form right angles with the adjacent inner faces of sides 19 of said corner members permitting the reception of the ends **75** 20 of the glass walls 20 of the aquarium.

The strip 16 does not extend to the lower end of the corner member 13, but is cut off as plainly seen on Fig. 4. Portion of said strip 16 equal to the height of the side wall **80** 21 of the tray 14 is undercut along the sides 19 of said corner members producing an L-shaped rabbet 22 adapted to receive the corner of the tray as plainly seen on Figs. 2 and 4. The resulting lug 23 will be positioned within the tray. The lower ends **85** 24 of the corner members 13 will provide legs or supports for the aquarium.

To strengthen the structure and further guide against leakage upright corner strips **90** 25 are provided. Said strips are of substantially trapezoid formation in cross section of which the narrower of the parallel walls 26 will abut the faces 17 of strips 16 and the wider parallel walls will remain exposed in the aquarium. The remaining walls of said strips 25 will contact with the inner faces of the ends of the glass walls as illustrated on Fig. 3. By means of screws **95** 27 said strips 25 are firmly fixed to the moldings 16 and corner members 13.

Side bars 28 and end bars 29 are positioned at the corners formed by the glass walls 20 and the bottom of the tray 14. The ends of bars 28 being suitably tapered closely abut the outer faces of the lower ends of strips 25, while the ends of bars 29 being properly beveled overlie the ends of bars 28 as plainly seen on Figs. 1 and 3. Both sets of said bars are affixed to the bottom of the **105** tray and to the base 10 by screws 30 or by like suitable means.

Corner plates 31 mounted upon the upper ends of corner members in addition to providing the ornamental touches for the aquarium serve for preventing any upward movement of the glass walls.

When desirable cement coating such as indicated by 32 in Fig. 3 may be applied to the contacting surfaces of strips 25 and bars 28 and 29. However, I have concluded that 10 the cement coating for said surfaces is not absolutely required to make the aquarium water-tight when constructed in accordance with the present disclosure. Water passing around the strips 25 will saturate wooden strips 16 causing distention thereof, and thus any pores between the walls 18 and walls 20 will be filled.

It is understood that should it be mechanically difficult to make rabbets 22 L-shaped 20 they may be made arcuate in which case the corners of the side wall 21 of the tray must be formed correspondingly.

From the hereinabove description it will be apparent that since the tray of the 25 aquarium is rabbeted within the corner members 13 any shifting or lateral displacement of said corner members will be prevented. Thus said rabbets 22 and lugs 23 will provide anchoring means for said corner members eliminating the use of any 30 braces at the upper ends thereof.

Pipe 32 and valve 33 are provided at the center of the bottom of the aquarium for 35 supplying the water. The wire basket 34 hinged or otherwise secured to the bottom of the aquarium and overlying the outlet of pipe 32 will prevent any impurities or gravel to interfere with the outlet of said pipe.

While there is described herein a preferred embodiment of the present invention, it is nevertheless understood that minor changes may be made therein without departing from the spirit and scope of the invention as claimed.

45 What I claim as new is:

1. An aquarium comprising a base, side ledges on said base, a tray upon said base inclosed within said ledges, corner members, side walls, connecting means between said tray and said corner members, and means 50 for holding said walls in position.

2. An aquarium comprising a base, side ledges upon said base, a tray upon said base

inclosed within said ledges, corner members, the adjacent ends of said ledges being spaced 55 for accommodating said corner members, side walls, connecting means between said tray and said corner members, and means for holding said walls in position.

3. An aquarium comprising a tray, corner members, longitudinal moldings within said corner members, said moldings having rabbets at their lower ends, lugs resulting from 60 said rabbets, the corners of said tray fitting into said rabbets, side walls positioned within said corner members and said tray, and means for holding said walls in position.

4. An aquarium comprising a tray, side walls, corner members, longitudinal moldings within said corner members, said moldings forming angles with the adjacent faces 70 at said corner members for accommodating the ends of said walls, means anchoring said corner members to said tray, and means for holding said walls in position.

5. An aquarium comprising a tray, side walls, corner members, moldings formed within said corner members, the lower ends of said moldings being undercut to form rabbets for accommodating the corners of 80 said tray, the longitudinal side walls of said moldings forming angles with the adjacent faces of said corner members for accommodating the ends of said side walls, and means for holding said walls in position.

6. An aquarium comprising a tray, side walls, corner members, moldings within said corner members, the ends of said moldings extending within said tray for preventing lateral movement of said corner members in 90 respect of said tray, said moldings spacing the adjacent ends of said walls, and strips overlying the faces of said moldings and of said adjacent ends of said walls for holding 95 said walls in position.

7. An aquarium comprising a tray, side walls, corner members inclosing the corners of said tray, the adjacent ends of said walls being positioned within said corner members, means for anchoring said corner members in said tray, and strips cooperating 100 with said means for holding the walls against displacement.

In testimony whereof I affix my signature.

WLADYSLAW GALANT.
